REEFING MACHINE

Bert A. Shannon, Long Beach, Calif.

Application December 9, 1946, Serial No. 715,127

1 Claim. (Cl. 262—13)

(Granted under the act of March 3, 1883, as
amended April 30, 1928; 370 O. G. 757)

1

This invention relates to a reefing machine for digging out calking, oakum, pitch and the like from the cracks between planks on a ship's deck.

In normal use of nautical vessels the material stuffed between the cracks in a deck planking becomes dry, rotted or cracked, and must be removed for the insertion of fresh material. This removal operation is known as "reefing," and has been accomplished in the past by means of a simple form of chisel held in the hand of a worker. By striking on the end of the reefing chisel while guiding the point in the crack, the old calking may be removed preparatory to insertion of new material.

This operation is not only slow but is very fatiguing, requiring frequent rest periods and leaving the worker exhausted at the end of the day's work.

It is an object of this invention to provide a machine for quickly removing calking from the crack between planks of a ship's deck.

It is another object to provide such a machine that may be operated by a worker with a minimum of effort and resulting fatigue.

It is another object to provide such a machine adapted to use, as its power source, conventional pneumatic reciprocating means known in the art.

It is another object to provide such a pneumatic powered machine on which the pneumatic means may be quickly and easily mounted and removed.

It is another object to provide a reefing bit especially designed to fit into the crack between planks of a ship's deck for removing calking material therefrom.

In accomplishing these and other objects of the present invention, I have provided improved details of structure, the preferred forms of which are illustrated in the accompanying drawing, wherein:

Fig. 1 shows a perspective view of the complete apparatus of this invention;

Fig. 2 is a side elevation of a modified form of the invention;

Figs. 3 and 4 are end and side views, respectively, of one form of reefing bit adapted for use in the machine of Fig. 1;

Figs. 5 and 6 are end and side views of another form of bit; and

Fig. 7 is a side elevation illustrating the manner in which the bit serves to remove calking material from a crack between planks of a ship's deck.

The machine of this invention comprises a pneumatic hammer mounted on suitable carrying means for movement along the crack between

2

planks of a ship's deck. The hammer receives a special reefing bit, and the two are disposed in a line approaching parallelism with the crack to be cleared of calking. Rapid and powerful reciprocation of the bit by the hammer causes the end of the bit to drive rapidly against the calking in the crack forcing it from the crack as the hammer is moved forward along the crack.

If desired, a metal plate may be provided having a slot therein through which the end of the bit projects into the crack, for protecting the edges of the plank immediately adjacent the crack. In addition, if found desirable, resilient means such as a tension spring may be provided to hold the bit from slipping completely out of the hammer.

Referring in more detail to the drawing:

The complete machine is shown in Fig. 1 comprising a carrying means 10 having a pair of elongated handles 11 and 12 extending upwardly from an axle 13 having wheels 14 and 15 mounted thereon. A U-shaped supporting member 16, secured as by welding between handles 11 and 12 near the bottom thereof, aids in supporting a pneumatic hammer 17, the upper end 18 of which is hooked over a cross-piece 19 secured between handles 11 and 12. Into the operating end of pneumatic hammer 17 is placed a reefing bit 20, the lower end 21 of which has a bend therein and a shoulder member 22 with a surface approximately horizontal and facing the digging portion or blade 23 of bit 20.

In the embodiment shown in Fig. 1 a metal shield 24 is shown mounted on axle 13 below bit 20, having a slot 25 through which blade 23 of bit 20 extends. This shield 24 serves both as a protector for the planks edges and as a guide for the bit 20. Because the shoulder 22 of the bit 20 reciprocates along the top surface of the shield 24, marring of the planks by impact of the shoulder 22 on their surface, is prevented. In addition, the plate 24 serves to maintain the proper angle of attack of the bit relative to the planks and to prevent biting in of the bit. The resiliency of this shield may also serve to bias the bit toward the chuck of the air hammer 17. Energy for pneumatic hammer 17 is provided in the form of compressed air fed through hose 26, the application of which is controlled by a button 27. Control button 27 is in turn actuated by a lever member 28 actuated through a control rod or rope 29, operated by any suitable means preferably attached to the ends 30 and 31 of handles 11 and 12. It will be seen that rapid and powerful reciprocation of bit 20 by hammer 17 drives blade

23 of the bit back and forth in the crack, forcibly removing the calking material, as carrying means **10** is directed along the crack by an operator grasping ends **30** and **31** of handles **11** and **12**, respectively.

In Fig. 2 is shown a modification of the invention having a pneumatic hammer **17a**, corresponding to hammer **17** of Fig. 1, and a bit **20a**, corresponding to bit **20**, mounted therein; the modification of Fig. 2 does not have the protecting metal shield **24**. In order to prevent bit **20a**, which frequently is merely slipped into a hole in the chuck of the pneumatic hammer and not secured in any other manner, from being completely driven from pneumatic hammer **17a**, a tension spring **32** is provided between bit **20a** and axle **13a**. The mounting of spring **32** on bit **20a** is preferably accomplished through a ring **33** held from sliding on bit **20a** by pegs **34** embedded therein.

In Figs. 3 and 4, an enlarged view of a particular form of reefing bit is shown. It will be noted that the bit **20b** has a slight bend **35** therein and an enlarged portion **36** on the bottom end of which is a shoulder **22b**. The surface of shoulder **22b** is substantially parallel to the deck planking in normal use of the machine. The actual digging portion or blade **23b** of bit **20b** extends from the shoulder **22b**. When bit **20b** is used with the metal shield **24**, shoulder **22b** rests against the top surface of shield **24** while blade **23b** extends through slot **25** into the crack to be cleared.

Figs. 5 and 6 show a bit **20c** similar to **20b** but having a deeper digging portion or blade **23c** for making a deeper removal of the calking in the crack.

Operation

Referring to Fig. 7, the manner in which a bit, for example bit **20c**, removes calking **37** from a crack **38** between planks will be evident. Blade **23c** extends through slot **25** in shield **24** and bit **20c** is rapidly reciprocated by pneumatic hammer **17**. This causes blade **23c** to move back and forth in the crack removing the calking as shown at **39**. The bit is caused to move forward in the crack **38** by appropriate guiding of carrying means **10** along the crack.

In operation, an operator grasps handles **11** and **12** and directs the point of blade **23** into the calk-

ing of the crack. He then pulls the rod **29** causing pressure on button **27** which applies air to pneumatic hammer **17**. The resulting reciprocation of bit **20** drives blade **23** into the calking, digging it out from the crack. The operator then guides carrying means **10** along the crack, clearing the entire crack of calking to a desired depth as determined by the character of blade **23** on bit **20**.

While I have shown but certain embodiments of my invention, it is susceptible to further modification without departing from the spirit of the invention. I do not wish, therefore, to be limited by the disclosures set forth, but only by the scope of the appended claim.

The invention described herein may be manufactured and used by or for the Government of the United States of America for governmental purposes without the payment of any royalties thereon or therefor.

I claim:

A reefing machine comprising a pneumatic hammer, a reefing bit attached to said hammer and adapted to fit into the crack between the planks of a ship, a shoulder on said bit adjacent and generally facing one end thereof, a wheeled carrying means therefor, a planking shield stationarily mounted on said carrying means, said shield having a flat horizontally disposed portion with an elongated slot therein, said hammer and bit being so mounted on said carrying means that said bit extends through and is reciprocable within and has a component of movement longitudinally of said slot.
